Primary Examiner — Karen S Acker(74) *Attorney, Agent, or Firm* — Rosenberg, Klein & Lee(57) **CLAIM**

The ornamental design for a mesh-chair cloth, as shown and described.

DESCRIPTION

FIG. 1 is a perspective view, taken from the front, top, and right side of a mesh-chair cloth showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.
